UNITED STATES PATENT OFFICE.

JOHN HENRY MARSH, OF MANCHESTER, ENGLAND.

DRAG OR TENSIONING MOTION.

Application filed January 24, 1924. Serial No. 688,205.

To all whom it may concern:

Be it known that I, JOHN HENRY MARSH, a subject of the King of Great Britain and Ireland, and a resident of Swinton, Manchester, in the county of Lancaster, England, have invented a new or Improved Drag or Tensioning Motion, of which the following is a specification.

This invention relates to means for applying tension to textile yarns as they are being wound from one winding point to another, and is particularly applicable to what is known as a drag motion in textile winding machines, which drag motion has for object the applying of tension to cotton or other yarn as it is being wound, say from a cop, cheese, cone or the like yarn package to a winding bobbin or the like. It has for object a means for ensuring that the exact tension required may be put upon the yarn being wound, according to the counts of yarn being handled, with means for easily and accurately varying the tension. A further feature of the invention is that in a winding or analogous machine all the drag motions comprised in the machine—being one drag motion for each winding point—may be simultaneously and accurately adjusted by one movement.

In carrying the invention into effect I mount a drag or tension wheel on the winding frame between the winding off point of a thread, and which point may be a cop, cheese bobbin or the like of yarn, and the winding on point which may be a bobbin or the like, the thread passing completely around the drag wheel in its passage between these two points. The rotation of the drag wheel operates a centrifugal governor which, at a predetermined speed of the wheel, brings into action a retarding brake to retard the drag wheel and thus put tension on the thread passing therearound. The retarding brake is screw adjustable to vary the time at which it may be brought into action for this purpose, and as a result any desired tension may be put upon the yarn thread being wound, the tension depending upon the difference between the peripheral speed of the drag wheel and the linear speed of the thread in its passage from one point to another. To adjust all the brake actions of one side of a frame simultaneously, a shaft is employed bearing spur wheels each of which meshes with a

toothed wheel which serves as adjusting device for a drag motion.

In winding and like frames a large number of yarn threads are invariably wound simultaneously, and the apparatus as now to be described and illustrated is for one thread only, the tensioning device for the other threads being, of course, identical throughout the machine. In the drawings:

Figure 1 is a side elevation of a drag wheel and the governor and braking apparatus, mounted within a casing;

Figure 2 is a detail view in elevation of centrifugal governing means, specially arranged in relation to the drag wheel shaft for a purpose hereinafter explained;

Figure 3 is a plan of the casing and wheel of Figure 1; and Figure 4 is a side elevation thereof;

Figure 5 is an end view of means for adjusting the retarding brakes of a plurality of tensioning devices, in one winding frame, simultaneously;

Figure 6 a front elevation of part of such means; and

Figure 7 shows diagrammatically a means for employing a plurality of drag wheels for one yarn thread, one of the wheels being governed according to this invention.

Referring to the drawings, Figures 1 to 4, 7 is a metal casing formed with an extension 8 and having formed exteriorly thereof the rib or stake 9 which is tapped at 10 to receive a screw for securing in place a lid or cover 11 (shown as broken away) for the casing. Suitable means may be provided at the upper end of the casing to receive another screw for a similar purpose.

12 is a drag wheel formed with the flanges 13, 14, and 15, 16, 17, are guide eyes for the yarn thread X, which passes upwards from a winding off point below the casing,

through the guides 15, 16, around the drag wheel periphery as shown, and through the guide 17 to the winding on point above the drag wheel. The guide 17 is in the form of a drop pin fitting within an orifice in the projection 18 and in the top casing 7 for a

purpose hereinafter described, and it is supported in position as shown in Figure 1 by the tension of the yarn thread X. The wheel 12 is cylindrical and preferably hollow, having a closed top to which is secured in any convenient manner the end of a shaft

19 the lower extremity of which is journaled in a footstep bearing at the bottom of the casing 7. The strengthening rib 9 allows of a deep bearing being formed for this purpose. On the shaft 19 are pinned the collars 20 and 21, to the latter being pinned or otherwise secured the extremities of governor arms 22 formed of spring steel and bearing the hemispherical governor "balls" 23. The other extremities of the governor arms 22 are pinned to a collar 24 freely slidably on the shaft 19. The shaft 19 and the governor elements, with the sliding collar 24, are arranged as now to be described with reference to Figure 2: Upon the shaft 19 is fitted a circular disc 25 having an arm 26 longitudinal to the said shaft. A further and similar arm may if desired be formed with the disc 25 but on the other side of the shaft 19 (not seen in the figure.) The collar 24 is provided with the tubular extension 27; which is slotted at 28 to allow the arm 26 to make an easy sliding fit within the slot. Thus as the shaft 19 rotates and the governor balls fly outwards, the collar 24 slides up the shaft 19 and the arm 26, or arms where more than one are employed, ensure that there will be no looseness or irregular torque or twist on the governor arms 22, the collar 24 being rotated directly by the shaft 19 whilst at the same time being freely slidably thereon.

The collar 24 has attached thereto or formed therewith the disc 29 (Figures 1 and 2) serving as a brake disc; this disc being therefore movable along the shaft 19 in proportion to the centrifugal force exerted on the balls 23. Referring again to Figure 1, 30 is a brake arm having a shank or spindle 31 which passes through the extension 8 of the casing 7 and terminates in a threaded end 32, on which is fitted the contrate wheel 33 having collar 34, the wheel and collar being tapped for the purpose. A guide pin 31^a is fitted to member 31 and slides in a slot 31^b in extension 8. A helical spring 35 surrounds the spindle 31 and abuts against the floor of the casing 7 and against the thickened portion 36 of the brake arm. The latter bears a brake pad 37 which may be of any known frictional material, and which may be fitted in place in any known manner. It may for instance be fitted in place by the extremity of brake arm 30 being bent around it to hold it in position.

The general operation of the apparatus will now be understood. The yarn thread X passing through guides 15 and 16 and around the drag wheel 12 and through the guide 17 passes to the winding on point at a high linear speed, and thus rotates the drag wheel at a proportionate speed. Through the apparatus described the brake disc 29 begins to slide up the shaft 19 until it comes into contact with the brake pad

37, the rotation of the drag wheel being then retarded and its rotary speed settling down to a speed which depends upon the steady pressure exerted by the brake pad 37 upon disc 29 which transmits the retardation to the shaft 19 and hence to drag wheel 12. The rotary speed of the drag wheel thus becoming less than the linear speed of the yarn thread, tension is put upon the said thread by the retarded drag wheel 12. To obtain a variation of this difference for different counts of yarn, the brake pad 37 is brought nearer to or drawn further from the normal position of the brake disc 29 by rotating the regulator wheel 33 as will be understood; the spring 35 ensuring that the brake arm 11 remains in constant position wherever adjusted. The dependent limb 38 may be formed with the brake arm 30, to limit its downward movement, but this may be omitted, or shortened to widen the limits within which the brake may be adjusted.

The guide 17 as already stated is a drop pin, similar to those already in use in various textile apparatus, and a wire contact stop 39 is provided, one end being cranked as shown in Figure 1 and the other encircling the shaft 19 between the collars 20 and 21; making sufficient frictional contact with these collars to rotate with them. Should the thread α break or slacken during the winding operation the guide pin 17 will drop within the casing, the slackened thread no longer supporting it, and the rotating stop arm 39 will make contact with it. Friction is thus applied to the collars 20 and 21, such friction being sufficient to ensure that the rotation of the drag wheel will cease almost immediately the thread α ceases its pull upon such wheel.

Figure 3 shows a preferred method of fixing the guide 16 to the top of casing 7. The guide is formed of wire bent as shown, and the screw 40 screws down upon it to hold it in position. The guide 15 shown in this and other figures may have one extremity threaded to fit in a tapped hole in a lug or the like at the top of casing 7; thus serving both as a guide and as a means for securing the lid or cover, previously referred to, upon the said casing.

In Figure 1 and Figures 5 and 6 is shown fragmentarily a simple method whereby the brake arms of all the tensioning motions at one side of a frame may be simultaneously adjusted. The regulator wheel 33 is formed with teeth 41, which engage with teeth of a spur wheel 42 pinned or keyed to a shaft 43 which extends the whole length of one side of the winding frame and is mounted in appropriate bearings to rotate therein. At the end of the shaft 43 is fitted the crank 44 with handle 45. Thus, angular motion of the shaft through crank 44 will operate

the regulator wheel 33 of each tensioning device simultaneously, and the particular relation of the teeth of each spur wheel 42 to the teeth of a regulator wheel 33 will ensure that expansion or contraction of the shaft 43 due to changes in temperature will not affect the ratio of any wheel 42 and its regulator wheel 33.

In Figure 7 is shown diagrammatically a method whereby the thread α may make contact with a greater surface of drag wheel. 12 is the drag wheel having fitted thereto the regulating motions hereinbefore described, and 46 and 47 are further similar 15 wheels, mounted on vertical shafts in bearings on the frame behind the wheel 12, the three wheels being connected by spur gearing borne on their shafts; or the lower flange of a drag wheel (indicated at 14 in 20 the previous drawings Figures 1 and 2) may be formed with teeth for this purpose. The 25 yarn thread α may be led around the wheels in contact with their peripheries in the manner most suitable to give the desired surface contact therewith, any additional yarn guides required being provided.

The casing 7 may be mounted on a winding frame in any convenient manner. In Figure 4 is shown a bracket 48 attached to 30 casing 7, with an orifice 49 to allow of the bracket being fitted upon a pin or the like on the frame, a set screw 50 holding it in position.

The various parts of the apparatus may 35 be of suitable metal. The guides 15, 16, 17, as before stated may be of wire; the casing 7 may be of ordinary metal galvanized, or be of non-corrodible metal, and the drag wheel or drag wheels may be of non-cor- 40 rodible metal.

The details given above may be varied within wide limits without departing from the spirit of my invention. The arrangement described of the centrifugal motion 45 and of a brake pad to come into operation at any predetermined time as a result of such centrifugal motion imparted by the yarn thread to a drag wheel around which it passes can be varied considerably by any 50 person skilled in the mechanical arts.

I claim:—

1. Means for applying tension to a yarn thread as it passes from a winding off point to a winding on point, comprising a drag

wheel around which the thread passes and 55 which wheel is rotated by the thread, centrifugal means operated by the rotation of the drag wheel to bring into operation at a predetermined speed of the latter retarding means for such wheel, and variable 60 means for determining the speed point of the said drag wheel at which point the retarding means come into operation.

2. In means for applying tension to a 65 yarn thread as claimed in claim 1, retarding means for the drag wheel, comprising a centrifugal governor operated by the shaft on which the drag wheel is mounted, a brake disc rotatable with the shaft but slidable thereon and connected to the governor arms, 70 a retarding brake pad adapted to make contact with the sliding disc, and means for varying the normal distance between the slidable brake disc and the brake pad, for 75 the purpose hereinbefore set forth.

3. In combination with means for applying tension to a yarn thread as claimed in claim 1, guides for the yarn one of such guides being a drop pin normally sustained by the yarn thread and adapted to fall into 80 the path of an arm on the drag wheel shaft, for the purpose hereinbefore set forth.

4. In combination with the means for applying tension to a yarn thread as claimed in claim 1, further drag wheels adjacent to 85 the drag wheel of the apparatus, bearings for such ancillary drag wheels, and means for rotating the said ancillary drag wheels from the main drag wheel, substantially as hereinbefore set forth.

5. For use with a plurality of yarn thread tensioning means constructed as claimed in claim 1, a regulator wheel fitted on the threaded end of a brake member in each tensioning device and which brake member is 90 adapted to come into contact with a disc slidable under the action of the centrifugal means operated by the drag wheel of such device, a rotatable shaft extending the 95 length of a frame in which the plurality of tensioning devices is mounted, and toothed wheels mounted on such shaft, each such toothed wheel being in mesh with a regulator wheel, for the purpose hereinbefore 100 set forth.

In testimony whereof I have hereunto set my hand.

JOHN HENRY MARSH.
